Primary Examiner — Jack Reickel*Assistant Examiner* — Rachel A Voorhies(74) Attorney, Agent, or Firm — GrowIP Law Group LLC(57) CLAIM

The ornamental design for a display screen or portion thereof with a graphical user interface, as shown and described.

DESCRIPTION

The single view is a front view of a display screen or portion thereof with a graphical user interface.

The outermost dot-dash broken lines illustrate a display screen or portion thereof and form no part of the claimed design. The remaining broken lines, illustrating portions of the graphical user interface, form no part of the claimed design.

1 Claim, 1 Drawing Sheet(56)
